UNITED STATES PATENT OFFICE.

EDWARD L. LITTON AND JOHN J. BROWN, OF GAFFNEY CITY, S. C.

PLOW ATTACHMENT.

SPECIFICATION forming part of Letters Patent No. 268,699, dated December 5, 1882.

Application filed September 30, 1882. (Model.)

To all whom it may concern:

Be it known that we, EDWARD L. LITTON and JOHN J. BROWN, of Gaffney City, in the county of Spartaburg and State of South Carolina, have invented a new and Improved Plow Attachment, of which the following is a full, clear, and exact description.

This invention relates to an improvement in plow attachments; and it consists in the combination and arrangement of parts, substantially as hereinafter fully set forth.

Reference is to be had to the accompanying drawings, forming part of this specification, in which similar letters of reference indicate corresponding parts in all the figures.

Figure 1 is a side elevation of our improved plow with some parts in section. Fig. 2 is a plan view of the same inverted. Fig. 3 is a transverse section through the beam on line x of Fig. 1, and Fig. 4 is a perspective view of the stock to be employed for the plow to be attached.

We propose to attach a secondary beam, a , to the main beam b of any ordinary plow by means of arms or bars c, d , either slotted or provided with series of holes for bolting them both to beam b by bolts e to set the said secondary beam more or less distant from the primary one, the said arms being permanently connected to the beam a in any suitable way; but for the bar c we prefer to make it a branch of the side bar, f , of the stock or foot g , for the plow to be attached, said stock, and also the stock h of the beam b , being preferably made to consist essentially of two bars placed side by side with a space or slot, j , in which to connect braces k, l . In the case of the stock h its bars will form a yoke, m , embracing the beam b and connected above it by the bolt n ; but

stock g will preferably have one of its bars, o , 40 extended up alongside of the beam and fastened by a staple, p , and the other branching under beam b for the connecting-arm c and a brace thereto. The brace l may be detachably bolted to the end of the beam b and have 45 a series of holes, q , by which to shift it up and down thereon to alter the pitch of stock h , which is capable of shifting forward and backward on its bolt n as a pivot.

Besides connecting the beam a to beam b by the arms c, d , we also propose to connect it thereto by the adjustable slotted plate s and the rod t , said rod being jointed to the plate and the beam, to allow the beam a to be shifted toward and from beam b , and from the front 55 end of plate s we extend a draw-rod, u , forward through an adjustable eyebolt, w , fixed on the arm d , so as to be shifted along said arm and secured anywhere by a clamp-nut, x , that may be required to guide the plows. 60

Thus it will be seen that we may have a double or single plow at will, and it is to be understood that we do not limit ourselves to the particular form or construction of the plow-stocks here shown, and we may apply any 65 form and size of plows desired.

Having thus fully described our invention, we claim as new and desire to secure by Letters Patent—

The combination of the slotted plate s and jointed connecting-rod t with the beams a and b , standard g , and the adjustable arms c, d , substantially as described.

EDWARD L. LITTON.
JOHN J. BROWN.
